A. ANDERSON

MOLD CLEANING, HEATING, AND LAMPBLACKING DEVICE

UNITED STATES PATENT OFFICE.

ALEX ANDERSON, OF DETROIT, MICHIGAN, ASSIGNOR TO EARL HOLLEY, OF DETROIT, MICHIGAN.

MOLD CLEANING, HEATING, AND LAMPBLACKING DEVICE.

Application filed September 7, 1923. Serial No. 661,378.

To all whom it may concern:

Be it known that I, ALEX ANDERSON, a citizen of the United States, residing at 9299 Cascade Ave., Detroit, in the county of 5 Wayne and State of Michigan, have invented certain new and useful Improvements in Mold Cleaning, Heating, and Lampblacking Devices, of which the following is a specification.

10 This invention relates to an improved burner for the uniform disposition of lampblack upon a permanent metal mold and is also adapted for heating, cooling and cleaning the metal molds.

15 Figure I shows a cross sectional elevation of the burner taken on the plane I—I of Figure II.

Figure II shows the application of this burner to the mechanism described in the 20 co-pending application, Serial No. 633,903, filed 23 April, 1923, by myself.

In Figure I, A is the body of the burner. This burner is cored out and contains within it the passage B. This passage is provided at C with a threaded entrance which 25 serves as a supporting means for the burner and also as a conduit through which the combustible gas is admitted to the burner. The main casting A is also provided with a second entrance D through which the cooling, 30 cleaning and heating gases are admitted.

Outlets E are provided for the cooling, heating and cleaning gases and to these outlets E the nozzles F are connected which 35 direct the cooling, heating and cleaning gases against the surface of the molds. The cored passage B connects with the outlets G to which the nozzles H are threaded. 40 These nozzles H direct the flame of the carbon depositing gas against the surface of the molds. A drain plug J is provided in the casting A for removing any moisture that may be deposited therein from the 45 compressed air.

A flexible pipe K connects with the entrance C to the casting A. A second flexible pipe L connects with the entrance D. Compressed air and illuminating gas are supplied 50 through L and acetylene is supplied through K. A valve M controls the supply of illuminating gas. A valve N controls the supply of compressed air and the valve O to the pipe K controls the supply of acetylene.

The casting A is shown suspended by the 55 mechanism described in my co-pending application referred to, which consists of an arm P which rotates about a center piece Q and rides on an inclined track R, the track R being supported by the stationary arm S. 60 A roller T is provided to reduce the resistance to movement. The molds U V, which are shown in the open position, carry a projecting arm W which contacts with the arm P. The molds U V rotate about the same 65 center as the piece Q and the arm P. The arm W therefore carries the arm P and the casting A with the molds U V.

The track R, however, is inclined so that as the molds rotate the arm P and the casting A are raised until the arm P clears the arm W, upon which the casting A and the arm P return to their initial positions running down the inclined track R and re-engaging with the next succeeding molds. The 70 molds U V are carried by the rotating table X upon which the molds U V rotate and also move into and out of engagement with each other.

Operation.—Immediately prior to running the machine the valves O and M are closed, the valve N is opened and the molds are thoroughly cleaned by the compressed air issuing out of the nozzles F. The valve N is closed and the valve M opened, and 80 ordinary city gas ignited in the burners F. This gas flame is allowed to play on the molds U V until such time as they have reached a sufficiently high temperature, which is 500° or 600° F. The table X is 85 then rotated and another pair of molds are heated until all the molds on the table have been heated to the desired temperature. The valve M is then closed, the valve O is opened and the acetylene flame allowed to play upon 90 the molds U V, the gas issuing out of the nozzles H. The molds are thereafter coated with lampblack every time the table X carrying the molds U V rotates.

The metal molds are preferably protected 100 with the coating described in the U. S. Patent #1,453,593, issued to Daniel H. Meloche on the 1st of May, 1923.

I prefer not to use the nozzle H for the compressed air and I prefer not to use the nozzle F for the acetylene, for the reason that I have found it preferable to make the nozzle H $\frac{1}{16}$ " in diameter, whereas the noz-

zle F may well be $\frac{1}{16}$ " in diameter as a much greater rate of flow of compressed air or heating gas is desirable than is the desirable flow of acetylene or other lampblack 5 depositing gas.

What I claim is:

1. In a combined lampblack burner, cleaner and heater, a passage for the admission of lampblacking depositing gas, a separate chamber for the admission of heating and cleaning gases, burners for the heating 10

and cleaning gases, separate burners for the lamp-blackening gas.

2. A device of the character described comprising a casing having a plurality of passages therethrough terminating in jet nozzles, means for alternately admitting lampblack depositing, heating and cleaning gases through said passages to said nozzles.

In testimony whereof I affix my signature.

ALEX ANDERSON.
